HYDRAULIC JACK PUMP

Fred M. Siedenburg, Richmond Hill, N. Y.

Application July 24, 1947, Serial No. 763,269

3 Claims. (Cl. 103—215)

1

This invention relates to hydraulic jack pumps. It is an object of this invention to provide a hydraulic jack pump in which the fluid is contained in a hermetically sealed reservoir, which will be leak proof.

It is another object of this invention to provide a hydraulic jack pump with a flexible reservoir, permitting a compact construction and that is inexpensive to manufacture.

It is a further object of this invention to provide a hydraulic jack pump that will operate in any and all positions efficiently.

It is a further object of the present invention to provide a jack pump which has a flexible container for serving as a fluid reservoir whereby the same may be expanded and contracted with the inward and outward flow of fluid and whereby there will be no opportunity for air to collect within the fluid to interfere with the operation of the pump or jack to which it may be connected.

It is another object of the present invention to provide a pump adapted to be rested upon the ground and wherein the pumping unit comprises a simple element which is fitted into a container adapted to house the flexible reservoir and which has an operating lever extending from the opposite end of the pump. The pump being located externally of the casing and a whip piece extending over the casing to protect the same and provide a substantial rest for the pump.

According to the invention, there is provided a pump element which is threaded at one end and to which is connected a casing. The threaded projection extends into the casing and has a flexible reservoir connected to the same into which the fluid is stored and retained for use to be forced under pressure by the pump to a jack element remotely located from the pump. The flexible reservoir will expand and contract according to the contents of the fluid within the same and hence will allow no opportunity for air to be gathered into the reservoir. The casing which is threadedly connected to the pump will give protection to the flexible reservoir member.

A foot piece is extended over the casing and by means of the same it can be retained on the ground while a lever located at the opposite end of the pump is worked back and forth. The lever connects with a piston rod which extends into the pump. The piston is made of flexible material such as synthetic rubber and will draw fluid out of the flexible reservoir and force it upwardly through the tube extending to the jack. A valve is turned when the fluid is to be returned to the flexible reservoir.

2

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of the pump with the operating lever extending upwardly therefrom and the pump resting in the position in which it is retained from being operated.

Fig. 2 is a transverse longitudinal cross sectional view taken on line 2—2 of Fig. 1.

Fig. 3 is a vertical transverse cross sectional view taken on line 3—3 of Fig. 1.

Fig. 4 is a partial longitudinal vertical cross sectional view taken on line 4—4 of Fig. 2.

Fig. 5 is a transverse vertical cross sectional view taken through the pump on line 5—5 of Fig. 1.

Fig. 6 is a detail perspective view of the flexible reservoir.

The hydraulic jack pump, according to the present invention, includes a pump member 10 formed of a round piece of stock and having a bore 11 therein in which is operated a piston 12 of synthetic rubber material and a piston rod 13 extending outwardly through a fitting 14 in the rear end of the pump member 10, upon the base of which is a packing gland 14a. Above the fitting 14 is a stud 15 to which an operating arm 16 is pivoted as indicated at 17. The lower end of this arm pivotally connects with the piston rod 13 as indicated at 18. A long handle or lever 19 is fitted in the arm 16. In the forward end of the piston cylinder 11 there is a ball valve 21 which opens as the piston 12 is drawn outwardly whereby to draw in a charge of fluid from a flexible and expandable reservoir sack 22 secured around a projection 23 by an attaching ring 24. The sack 22 is in the form of a bag or tube made of rubber, synthetic material or any flexible, non-porous material hereinafter referred to as a flexible reservoir. The projection 23 also has threads 25 to which a casing 26 is attached. The casing 26 is provided with vent hole 26a and its purpose is to protect the flexible reservoir 22. This flexible reservoir 22 will contract as fluid is drawn from the same and will expand as fluid enters it. By having such a flexible reservoir, the air is prevented from entering the fluid as no air is permitted in the reservoir; also the reservoir, on contracting, maintains a constant contact upon the fluid.

In the pump member 10 there is a passageway

27 which is controlled by a valve 28. Normally the passageway 27 is closed so that fluid will pass upwardly through a hose connection 29 attached to the side of the pump member 10 to a jack element, not shown. When the valve 28 is loosened, the passageway 27 is opened and fluid will return through the flexible hose connection 29 to the flexible reservoir 22.

Surrounding the casing 26 is a guard plate or sleeve 31 roughened on its exterior, as indicated at 32, and which has a flat bottom 33 on which the pump is rested. A foot may be extended over the roughened portion 32 to retain it on the ground.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose leading from the cylinder for the discharge of liquid from the cylinder when the piston moves in the other direction, a collapsible reservoir for hydraulic fluid connected with the said adjacent end of the pump member in communication with the adjacent end of the passage, comprising a tubular sack of resilient material having one end closed and its other end engaged over the said adjacent end of the pump member, means securing the open end of said sack to the said adjacent end of the pump member, a rigid casing engaged about said sack and secured to the said adjacent end of said pump member to protect said sack, said casing being oval-shaped in cross section, and a guard sleeve engaged over said casing with the opposite portions of its inside face engaging opposite sides of said casing located on opposite sides of its plane of greatest width.

2. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose lead-

ing from the cylinder for the discharge of liquid from the cylinder when the piston moves in the other direction, a tubular sack of rubber having one end closed and its other end secured in position over the said adjacent end of the pump member to extend horizontally therefrom, a rigid casing oval-shaped in cross-section engaged about said sack and secured to the said adjacent end of said pump member to protect said sack, said casing having its greatest width arranged horizontally, and a guard sleeve substantially oval-shaped in cross-section engaged over said casing with its greatest width parallel to the greatest width of said casing and with the inner faces of its top and bottom walls in facial contact with the top and bottom of said casing.

3. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose leading from the cylinder for the discharge of liquid from the cylinder when the piston moves in the other direction, a tubular sack of rubber having one end closed and its other end secured in position over the said adjacent end of the pump member to extend horizontally therefrom, a rigid casing oval-shaped in cross-section engaged about said sack and secured to the said adjacent end of said pump member to protect said sack, said casing having its greatest width arranged horizontally, and a guard sleeve substantially oval-shaped in cross-section engaged over said casing with its greatest width parallel to the greatest width of said casing and with the inner faces of its top and bottom walls in facial contact with the top and bottom of said casing.

20 4. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose leading from the cylinder for the discharge of liquid from the cylinder when the piston moves in the other direction, a tubular sack of rubber having one end closed and its other end secured in position over the said adjacent end of the pump member to extend horizontally therefrom, a rigid casing oval-shaped in cross-section engaged about said sack and secured to the said adjacent end of said pump member to protect said sack, said casing having its greatest width arranged horizontally, and a guard sleeve substantially oval-shaped in cross-section engaged over said casing with its greatest width parallel to the greatest width of said casing and with the inner faces of its top and bottom walls in facial contact with the top and bottom of said casing.

25 5. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose leading from the cylinder for the discharge of liquid from the cylinder when the piston moves in the other direction, a tubular sack of rubber having one end closed and its other end secured in position over the said adjacent end of the pump member to extend horizontally therefrom, a rigid casing oval-shaped in cross-section engaged about said sack and secured to the said adjacent end of said pump member to protect said sack, said casing having its greatest width arranged horizontally, and a guard sleeve substantially oval-shaped in cross-section engaged over said casing with its greatest width parallel to the greatest width of said casing and with the inner faces of its top and bottom walls in facial contact with the top and bottom of said casing.

30 6. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose leading from the cylinder for the discharge of liquid from the cylinder when the piston moves in the other direction, a tubular sack of rubber having one end closed and its other end secured in position over the said adjacent end of the pump member to extend horizontally therefrom, a rigid casing oval-shaped in cross-section engaged about said sack and secured to the said adjacent end of said pump member to protect said sack, said casing having its greatest width arranged horizontally, and a guard sleeve substantially oval-shaped in cross-section engaged over said casing with its greatest width parallel to the greatest width of said casing and with the inner faces of its top and bottom walls in facial contact with the top and bottom of said casing.

35 7. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose leading from the cylinder for the discharge of liquid from the cylinder when the piston moves in the other direction, a tubular sack of rubber having one end closed and its other end secured in position over the said adjacent end of the pump member to extend horizontally therefrom, a rigid casing oval-shaped in cross-section engaged about said sack and secured to the said adjacent end of said pump member to protect said sack, said casing having its greatest width arranged horizontally, and a guard sleeve substantially oval-shaped in cross-section engaged over said casing with its greatest width parallel to the greatest width of said casing and with the inner faces of its top and bottom walls in facial contact with the top and bottom of said casing.

40 8. In a hydraulic jack pump having a pump member formed with a cylinder housing a reciprocal piston and a passage continuing from the end of the cylinder to the adjacent end of the pump member and including a one-way valve arranged to permit fluid to be sucked into the cylinder when the piston moves in one direction and a hose leading from the cylinder for the discharge of liquid from the cylinder when the piston moves in the other direction, a tubular sack of rubber having one end closed and its other end secured in position over the said adjacent end of the pump member to extend horizontally therefrom, a rigid casing oval-shaped in cross-section engaged about said sack and secured to the said adjacent end of said pump member to protect said sack, said casing having its greatest width arranged horizontally, and a guard sleeve substantially oval-shaped in cross-section engaged over said casing with its greatest width parallel to the greatest width of said casing and with the inner faces of its top and bottom walls in facial contact with the top and bottom of said casing.
